UNITED STATES PATENT OFFICE.

CLARENCE W. DOLL, OF INDIANAPOLIS, INDIANA.

COMBINATION AND ARRANGEMENT OF ROTARY WEB-PRINTING MACHINES.

1,074,699.

Specification of Letters Patent.

Patented Oct. 7, 1913.

Application filed April 2, 1910. Serial No. 553,071.

To all whom it may concern:

Be it known that I, CLARENCE W. DOLL, a citizen of the United States, residing at Indianapolis, in the county of Marion and 5 State of Indiana, have invented certain new and useful Improvements in the Combination and Arrangement of Rotary Web-Printing Machines, of which the following is a specification.

10 This invention relates to the combination and arrangement of rotary web printing machines and has for its primary object to provide an improved combination and arrangement of a plurality of presses whereby 15 time may be economized and the operation of the presses made more efficient in the production of newspapers and the like ranging from two to any required number of pages usually assembled by presses of this nature.

20 One of the objects of this invention is to make it possible to utilize all of the press sections at times when according to old, well known plans of arrangement, one fourth to one half of the press sections remained idle 25 and non-productive.

Another object is to have all of the press sections co-operatively arranged with their bases in substantially the same plane or on a common base plate.

30 Still another object is to arrange the presses in such order as to provide ample working space around each press.

Another object is to provide means for operating the press sections in separate 35 groups independently of each other and to provide a plurality of power units having means for coupling said power units up to any or all of the said groups.

To the accomplishment of these and other 40 objects as will appear in the specification, the invention consists in the combination and arrangement of parts exemplified in the drawings and more specifically pointed out in the claims.

45 In the drawings, Figure 1 is a side elevation of the left end of one side of a battery of six double presses embodying my improvements, parts of the foundations being broken away to show one of the power units 50 with its driving connections. Fig. 1^a is a similar side elevation of the other end of the same battery. Fig. 2 is a top plan view,

partly in section, of the entire battery of presses. Fig. 3 is a diagrammatic plan view of the base frames and shafting connections 55 with the couplings therefor. Fig. 4 is an end elevation taken from the right of Fig. 1^a with the folding mechanism removed. Fig. 5 is an end elevation from the right of Fig. 1^a showing the folding mechanism dia- 60 grammatically.

On the basis that in newspaper calculations eight pages are considered as a unit, a press which prints eight pages is called a single press, and one which prints sixteen 65 pages is called a double press. Accordingly, in the embodiment of the invention shown in the drawings, a battery of six double presses each capable of printing sixteen pages, is provided. These sixteen-page sec- 70 tions are, in the present embodiment, arranged in two parallel rows with their bases in the same plane to form three pairs of double presses. Each of said rows is pro- 75 vided with a folder at each end.

Referring first to Fig. 2 of the drawings, the double presses are represented generally by the letters A, B, C, D, E, and F. Inasmuch as all of these presses are substantially the same, a description of one double 80 section will be sufficient for all. Referring to section A, as shown in Figs. 1^a, 2, 3, 4 and 5, the base frame 1 of said section is mounted in any suitable manner, not specifically concerned in the present invention, upon any 85 suitable foundation, such as the masonry 2. Rigidly mounted on the base 1, are side frames 3 and 4 wherein may be mounted a plurality of plate cylinders, impression cylinders, ink ductor rolls, inking rolls, etc., in 90 a well known manner. Projecting vertically from the side frames 3 and 4 in substantially the same planes therewith, are the parallel extension frames 5 and 6 between which are supported in any suitable manner a pair 95 of angle bars 7 and 8 arranged at an inclination to said frames in one direction and a pair of angle bars 9 and 10 arranged with an opposite inclination, said bars 7 and 8 being arranged in different planes and in 100 planes different from those of the angle bars 9 and 10. By means of this arrangement, a web having been printed in the usual manner and divided by a slitter 11 may be

directed by said angle bars either toward the folder at the end of the press or may be directed across to the companion press B paired therewith. The several presses are thus adapted to pass their printed webs from one to the other or to the folders in accordance with the operating plans to be hereinafter referred to. The web from a large roll of paper 12 may be guided to the printing rolls in any desired manner. Said roll 12 is mounted in the side frames 3 and 4 in bearings 13 and 14 disposed adjacent to the floor of the press room thereby facilitating the positioning of the roll 12 preliminary to operating the press. As will be seen from an inspection of Fig. 3, ample space is provided between each pair of double presses and between the two presses of each pair, thus facilitating all work in connection with the operation of the presses.

Referring now more especially to Figs. 1^a and 2, at the end of the battery of double presses a roller frame casting 15 projects on one side from the side frame 3 and a corresponding frame casting 16 is arranged on the opposite side extending from the side frame of the press section B. Intermediate of the roller frames 15 and 16 is a third frame 17. The outer projecting ends of said frames are supported preferably by means of one of the side frames 18 (see Fig. 1^a) of the folding mechanism to be again referred to. Journalled within the guide roller frames 15, 16 and 17 are a plurality of guide rollers 19 and 20, suitably arranged and grouped to direct the printed webs from the several presses to the folding mechanisms in accordance with the methods of working the presses to be hereinafter indicated. Said guide rollers include a series of compensating rollers which are designed and arranged to equalize the irregularities of the printed sheet margins running as they do as idler rollers and being turned by the printed sheets passing over and under them. In addition, at suitable points there are positioned bracket arms projecting either upwardly or downwardly over the folder frames, said brackets being provided with bearings for iron rollers, which are driven by friction from the printed sheet. These idler rollers are spaced apart so as to prevent the printed sheets from touching each other until they have been assembled at the top of the folding former.

Referring more especially to Figs. 1^a and 5, the folding mechanism comprises the idler rollers for guiding the webs thereto, a folding former 21, there being one of these folding mechanisms at each end of each row of double presses. Said former 21 is disposed with its nose inwardly toward the end press A and is adapted to double the paper preliminarily to passing it between the guide rollers 22, said rollers 22 being

positioned a little in advance of creasing rollers 23. After passing through the creasing rollers 23, the folded web is passed through the compression rollers 24, which compression rollers are driven in any suitable manner, preferably by a chain of gears from the drive shaft 32 to be presently referred to again. Should it be desired to assemble the web or webs from the press B (see Fig. 5) onto the web or webs from press A, a guide roller 26 adjacent to and a little to one side of the creasing rollers 23 over which the doubled web may be passed on its way to a transfer guide roller 27, there preferably being a compensating roller 28 interposed between the guide rollers 26 and 27. From the guide roller 27 which is preferably mounted in the folder frame, the doubled web may be passed to the creasing rollers 23 of the press A and there assembled with the folded web from said press and passed together through the compression rollers 24 of the press A.

Referring now more especially to Figs. 1, 1^a and 3, the combination and arrangement of drive shaft sections, clutches, and power units will be readily understood. In the embodiment shown in the drawings, the shafting is arranged in nine sections with the adjacent ends of contiguously disposed sections provided with clutch elements enabling said sections to be connected and disconnected in order to enable one or more sections of the presses to be driven from a single motor or from all of the motors combined in a manner to hereinafter be made clear. For this purpose the press sections A, E and F shown in side elevation in Figs. 1 and 1^a, are provided with shaft sections 29, 30, 31 and 32, said sections being journaled in hangers numbered 33 to 42 inclusive. Such sections are preferably co-axially arranged in the manner shown and provided with clutches 43, 44, and 45, whereby said sections may be connected to run as a single shaft or divided up into sections in the manner hereinafter indicated.

Extending rearwardly from the shaft section 32 and preferably in the same plane therewith is a short section 46 which is geared by bevel gears 47 to the section 32. The rear end of section 46 may be connected to the forward end of the short section 48 by means of a clutch 49, said section 48 being geared at 50 with a shaft section 51 which extends through the press section B and across to the press section C. A short shaft section 52 is also disposed to extend rearwardly from the section 29 to which shaft it is geared by means of bevel gears 53. This shaft section 52 is geared at 54 to a shaft section 55, extending through the press section D. The end shaft sections 29, 32, 51 and 55 extend through to the outside of the folding mechanisms and are provided with

gears 56, 57, 58 and 59 respectively for driving said folding mechanisms.

Arranged below the common base of the printing press sections A, B, C, D, E and F, and preferably in a sub-basement for that purpose, are a plurality of power units which may be connected up separately or together with the different press sections by means of the shaft sections and clutches just referred to. Said power units are preferably a series of electric motors 60, 61 and 62, the disposition of said motors being exemplified, as shown in the drawings, by placing the motor 60 under the press section E and gearing it directly to the shaft section 29 as shown. Again, the motor 61 is preferably disposed beneath press section F and geared directly to the shaft section 31 and the third motor 62 is disposed preferably beneath the press section B and geared directly to the shaft section 51. It will be evident therefore that the presses may be driven by the respective motors in the following combinations, there being the usual means such as removable idler gears or the like for connecting or disconnecting each individual press from the drive shafts. First, the two center sections C and F may be cut out and the four end sections A, B, D and E, run separately. With this arrangement the paper after printing eight pages or less will run on section A and turning on angle bars thereabove pass to the adjacent folding mechanism. In a similar manner, the printed web from press sections B, D and E will pass respectively to their adjacently disposed folding mechanisms. With this arrangement, if desired, all the motors may be used together with all the clutches closed or may be used separately by having clutches 43, 44, and 49 open. To run ten and twelve-page papers, full capacity, the press sections may be run as two machines containing three sections each, that is, sections A, B and C may be run together driven by motor 61 or 62 for one machine, and sections D, E and F running together and driven by motor 60 or 61 for the other machine. To run ten-page papers from four folders, pages 1, 2, 3, 4, 7, 8, 9 and 10, may be run on section A being passed over to the folder adjacent to press section A by means of the angle bars and guide rollers hereinbefore referred to, pages 5 and 6 being run on press section B and being passed up through the angle bars thereabove, crossed over and turned to intersect the other pages on section A and passed onto the folder of section A. In another way, pages 1, 2, 9 and 10 may be run on section B and passed over to the folder adjacent to said section, while pages 3, 4, 5, 6, 7 and 8 may be run on section C, and passed over section B to intersect the other pages from section B and to pass on to the folder

for section B. Sections D, E and F and the folders adjacent to end sections D and E may be dressed in a similar manner.

In order to get twelve-page papers from four folders, the motors and printing sections may be run the same as described for ten pages, pages 1, 2, 3, 4, 9, 10, 11 and 12 being run on section A and passed to the folder for said sections while pages 5, 6, 7 and 8 may be run on section B and be passed over to intersect the other pages and then onto the folder for section A; or pages 1, 2, 11 and 12 may be run on section B and passed onto the folder for section B, while pages 3, 4, 5, 6, 7, 8, 9 and 10 may be run on section C and passed over to intersect the other pages on section B and then onto the folder for section B. Press sections D, E and F with the folders adjacent to the end sections D and E may be dressed in a similar manner. To run fourteen, sixteen, twenty-eight and thirty-two pages, the presses may be divided into three separate machines, sections A and F being run together and driven by motor 61, sections B and C being run together and driven by motor 62 and sections D and E being run together and driven by motor 60. With this arrangement sections A and F deliver the web to the folder for section A, the webs from sections B and C are delivered to the folder for section B and the webs for D and E can be delivered to either of the folders adjacent thereto. In fact, the folders on each end of the press being equipped with the transferring rollers already referred to are adapted to deliver complete papers in single sections or from two to four sections all inserted. The presses may be operated for any combination of pages ranging from two to ninety-six and with a great saving of time and machinery.

By means of the combination and arrangement of press sections, together with the driving and clutch elements as hereinbefore described, by far the larger amount of the labor connected with the printing operations, can be performed from the floor of the press room, thereby necessitating the employment of fewer men and less labor than is at present required with well known arrangements.

It will be obvious that by means of the combination and arrangement of the perfecting printing mechanisms which are provided with inking, plate and impression cylinders, folding mechanisms, and sectional shafting and clutches located in the manner described will make available many more combinations and arrangements such as are instanced above. The presses are, moreover, provided with means for greatly increasing the efficiency over what has heretofore been possible with present well known orders of arrangement.

What I claim is—

1. The combination of a plurality of perfecting printing presses arranged in opposite pairs, the said pairs being spaced apart 5. to permit access to each press on all sides, means for connecting said presses to run in groups having any desired number in each group, and means for driving each group independently and simultaneously.
10. 2. The combination of a plurality of double perfecting printing presses arranged in parallel rows on a common base, two of said presses being provided with common drive shaft sections and the other of said 15. presses being provided with a drive shaft, and means for connecting all of said drive shafts in operable relation to each other and in separate groups.
20. 3. The combination of a plurality of double perfecting printing presses arranged in parallel rows on a common base, some of said presses being provided with a common drive shaft section and the other of said 25. presses being provided with a drive shaft, a folder geared to each end press shaft and operable from its drive shaft with or without said end press in any desired grouping; and means for connecting all of said drive shafts in operable relation to each other in 30. any desired grouping.
35. 4. The combination of a plurality of double perfecting printing presses, each double press being provided with a drive shaft section, and two of said double presses each having an additional common drive 40. shaft, and means for connecting all of said drive shafts in operable relation to each other and in any desired groups.
45. 5. The combination of a plurality of double perfecting printing presses, each double press being provided with a drive shaft section, and two of said double presses having an additional common drive shaft, means for connecting all of said drive shafts in operable relation to each other; and means whereby one section of each of the double presses having the common additional drive shaft may be operated independently by said common additional drive 50. shaft.
55. 6. The combination of a plurality of double perfecting printing presses having their bases in a common plane, means for connecting said presses to run in any desired grouping and means for driving each group independently.
60. 7. The combination of a plurality of double perfecting printing presses having their bases in a common plane, means for connecting said presses to run in any desired grouping, means for driving each group independently, and a folding mechanism for each group.
65. 8. The combination of a plurality of double perfecting printing presses arranged on a common base plate, means for connecting said presses to run in groups having any desired number in each group, means for driving each group independently, and folding mechanism for each group to the folding mechanism for that group.
70. 9. The combination of a plurality of double perfecting printing presses arranged in rows on a common base plate, a folding mechanism at each end of each row, means for operating said presses independently or in groups, and means for guiding a web from each press to one of said folding mechanisms in either row.
75. 10. The combination of a plurality of double perfecting printing presses arranged in rows with their bases in a common plane, said presses being oppositely disposed in 80. pairs, a folding mechanism at each end of each row, means for operating said presses independently or in groups, and means mounted on each pair of presses for guiding a web from each press to one of said folding 85. mechanisms in either row.
85. 11. The combination of a plurality of double perfecting printing presses arranged in parallel rows on a common base, a folder mounted on said common base at each end of each of said rows, said folder being disposed with its nose presented inwardly toward the presses, and means for transferring printed sheets from one folder to another for assembling a plurality of sections.
90. 12. The combination of a plurality of double perfecting printing presses arranged in pairs in two parallel rows on a common base and with the cylinders of said presses arranged longitudinally of said rows, a folder at each end of each row, means for operating said folders separately or in pairs, and guide and compensating rollers arranged intermediately of adjacent folders for transferring printed sheets from one 95. folder to another.
100. 13. The combination with a plurality of perfecting printing presses arranged in parallel rows on a common base, a folding mechanism at each end of each row, a plurality of angle bars mounted above said press, some of said bars being arranged to guide a web in one direction and others of said bars being arranged to guide a web in the opposite direction along said rows, a plurality of rollers arranged adjacent the ends of said rows to guide the webs to said folding mechanisms, means for operating said folding mechanisms separately or together, and means for guiding the webs from one 105. folding mechanism to another.
115. 14. The combination of a plurality of double perfecting printing presses arranged in parallel rows on a common base, two of said presses being provided with a common 120. base plate, means for connecting said presses to run in groups having any desired number in each group, means for driving each group independently, and folding mechanism for each group.
125. 15. The combination of a plurality of double perfecting printing presses arranged in parallel rows on a common base, a folder mounted on said common base at each end of each row, said folder being disposed with its nose presented inwardly toward the presses, and means for transferring printed sheets from one folder to another for assembling a plurality of sections.

drive shaft section and the others of said presses being provided with their respective drive shafts, a folder geared to each end press, and means for connecting all of said 5 drive shafts in operable relation to each other.

In testimony whereof I have signed my

name to this specification, in the presence of two subscribing witnesses, on the 24th day of March A. D. 1910.

CLARENCE W. DOLL.
